UNITED STATES PATENT OFFICE.

MORRIS WINNING, OF OTTAWA, ONTARIO, CANADA.

SWITCH.

1,267,951.

Specification of Letters Patent. Patented May 28, 1918.

Application filed September 15, 1917. Serial No. 191,622.

To all whom it may concern:

Be it known that I, MORRIS WINNING, a subject of the King of Great Britain, and a resident of the city of Ottawa, in the 5 Province of Ontario and the Dominion of Canada, have invented certain new and useful Improvements in Switches, of which the following is a specification.

This invention relates to improvements in switches adapted to be used on street rail-ways, narrow gage tracks, and on railways generally, and is of the type described in my co-pending application No. 166,250, and the objects of the invention are to facilitate 10 operating a track switch from the approaching car or train, so that the desired path of travel may be taken without stopping the car or train to manually change the switch; to simplify the construction of the switch 15 actuating mechanism on the car and render it capable of being used on cars at present in use, and generally to adapt the several parts to better perform the functions required of them.

With the above and other objects in view, the invention consists essentially of the improved construction particularly described and set forth in the following specification and accompanying drawings forming part 20 of the same.

In the drawings:

Figure 1 is a fragmentary sectional elevation of a railway track and car showing the switch actuating mechanism mounted 25 thereon.

Fig. 2, is a vertical section of the depressible plunger designed to actuate the track mechanism.

Fig. 3 is an elevation of the same.

Like characters of reference refer to like parts in the several figures.

Referring to the drawings, A represents a railway track, and B a car, the said track being provided with a switch mechanism C 45 designed to be actuated by the car mechanism D in the manner to be made clear hereafter.

The track mechanism consists of a crank shaft 10, which is adapted to actuate the switch in the manner disclosed in my co-pending application No. 166,250, being provided in one end with a gear 11 adapted to mesh with the gear 12 carried by the vertical spindle 13 which is provided in the upper 55 end with a star wheel 14. As the star wheel is rotated in a horizontal plane, the shaft 10

is rotated, and the crank of the said shaft actuates the switch. It is not thought necessary to further describe this part of the device, as it does not form a part of the present 60 invention.

The car mechanism B comprises a stand-ard 15 mounted on the deck 16 of the car, and provided with a slot 17 in the lower end, and having an upper bifurcated end 18. 65 Slidably mounted in this standard A is a plunger 19 provided intermediate of its length with a foot pedal 20, which slidably engages with the slot 17 and projects there-through, so that the motorman or driver may 70 depress the plunger 19 by exerting pressure on the foot pedal.

This plunger is also designed to be hand actuated and to this end I provide a cam 21 pivotally mounted on the bifurcated end 18 75 of the standard, the said cam being held in a normal elevated position by a spring 22, but on rotation of the cam the plunger 19 will be depressed.

This plunger is adapted to be normally 80 held in an elevated position and is provided with a collar 23 above which a spring 24 is located, the said spring engaging at its upper end with the washer 25 on the plunger and located below the deck of the car. 85

On the lower end of the plunger 19 a ver-tical roller 26 is rotatably mounted and below this roller a wheel 27 is journaled. When a car or train equipped with this mechanism is approaching a switch the 90 driver or motorman may rotate the cam 21 by hand to depress the plunger 19 to the desired extent so that the vertical roller 26 will engage with the star wheel 14 and ro-tate the same so actuating the crank shaft 10 95 and throwing the switch in the desired direc-tion.

By providing the roller 26 excessive fric-tion on the plunger 19 is eliminated while the wheel 27 will make rolling contact with 100 the ground should the plunger on depression engage the same and the use of the wheel 27 will thus prevent any sudden force being exerted on the plunger which would tend to bend the same.

In the event of the motorman's or driver's hands being occupied at the precise moment at which the switch is to be thrown, he may actuate the plunger by placing his foot on the pedal 20, thus leaving his hands free. 105

After the pressure has been released from the foot pedal 20, the plunger 19 is returned 110

to its normal position under the action of the spring 24. If the plunger 19 has been actuated by the cam 21, the said cam on being released will be returned to its normal position by the spring 22, allowing the plunger 19 to be returned to its normal position by the spring 24.

From this description it will be seen that I have invented a switch actuating mechanism which can be advantageously used on street and railway cars, so that the switch may be thrown when a car or train is approaching the same, the said mechanism being capable of being actuated by foot or hand, in a manner to suit the convenience of the operator.

As many changes could be made in the above description and many apparently widely different embodiments of my invention within the scope of the claims constructed without departing from the spirit or scope thereof, it is intended that all matter contained in the accompanying specification and drawings shall be interpreted as illustrative and not in a limited sense.

What I claim as my invention is:

1. A switching device of the class described including track means, car means for operating the track means consisting of a standard, a plunger slidably mounted in the standard, a roller on the lower end of the plunger, a wheel below the roller, resilient means for returning the plunger to a normal position, a foot pedal on the plunger, and a manually operated cam on the standard co-acting with the head of the plunger. 35

2. A switching device of the class described including track means, car means consisting of a standard, a plunger slidably mounted in the standard, a roller on the lower end of the plunger, foot means for actuating the plunger, a hand controlled cam on the top of the standard co-acting with the top of the plunger, and resilient means for holding the cam to normally permit of the plunger being held in an elevated position. 40 45

In witness whereof I have hereunto set my hand.

MORRIS WINNING.
